F. D. SAYLOR.

ELECTRICAL CONDUIT

Filed Feb. 13, 1923

Inventor:

Frank D. Saylor
by Chas. F. Perkins Attorney

UNITED STATES PATENT OFFICE.

FRANK D. SAYLOR, OF WHEELING, WEST VIRGINIA, ASSIGNOR OF ONE-HALF TO
RUSSEL DART, OF NEW YORK, N. Y.

ELECTRICAL CONDUIT.

Application filed February 13, 1923. Serial No. 618,825.

My invention relates to improvements in non-metallic flexible conduits for electric conductors, and in the method of manufacturing the same.

5 The object of my invention is to produce an efficient conduit of the character named at a minimum cost, and to produce a paper string or cord which is especially fitted and adapted for use as a helical woof or filling 10 in the manufacture of such conduits.

It is essential that such conduits should be able to maintain their cylindrical form under the usual lateral pressure to which they are subjected, and also when flexed to 15 form curves and bends during the installation of the conduits for interior use in buildings. It is also important that the wall of such conduits should be firm and strong in order to serve its purpose as an armor 20 to protect the insulation of the enclosed conductor from abrasion and from other injuries from violence during transportation in the process of installation. It is also necessary because of the market conditions 25 and keen competition, that such articles be produced at a minimum cost. With these objects in view I have devised the conduit illustrated in the accompanying drawing in which Fig. 1 is a perspective view of a 30 conduit embodying my invention; Fig. 2 is a cross section of the cord forming the helical member or woof of the conduit; Fig. 3 is a diagram illustrating the method of forming the string or cord.

35 Referring to Fig. 3 of the drawing, 4 is a strip of tissue paper approximately a half inch wide wound upon a suitable spool or bobbin. 5 is a cotton or other textile thread or string designed to form a core for the 40 finished string or cord. In the manufacture of the cord the thread 5 is fed through a bath of sizing contained in the trough 6, then into the V-shaped former 7 together with the paper strip 4, the latter being 45 wrapped around the thread 5 by the action of the V-shaped former when the paper strip 4 and the thread 5 are drawn through the same by any suitable means. The thread 5 becomes not only thoroughly saturated 50 but coated with the sizing, and the paper strip 4 becomes saturated with it by absorp-

tion of the sizing which adheres to the surface of the thread 5. Below the former 7, the thread 5 wrapped in the paper strip 4, is drawn through a die 8 for the purpose of 55 compressing them together, and they are then drawn through any of the well known machines for twisting paper strips and forming paper cord. The sizing is thereby squeezed into the pores and interstices of the paper and the thread, thoroughly impregnating the same so that they become practically a homogeneous substance, which when thoroughly dried forms a hard and highly resilient cord. I am 60 aware that paper cord has been treated with sizing and other stiffening compounds before my invention and that a thread has been enclosed in the paper strip, and I make no claim to the same. The novelty of my 65 invention resides in enclosing the thread while saturated and coated with the fresh sizing in the porous paper strip and thereby insuring a complete impregnation of the finished cord with the sizing which cannot 70 be accomplished merely by subjecting the finished paper cord to an external bath of sizing.

In Fig. 1 I have shown a non-metallic flexible conduit embodying my invention, 80 combining a helical member or weft 9 of paper cord made by the method hereinbefore described, and warp threads 10 of cotton or other suitable material woven upon one of the familiar types of circular 85 loom adapted for the purpose of forming tubing of the character described.

The conduit made by my method possesses a hard and firm wall and yet is readily flexed without flattening and is produced at 90 comparatively low cost.

What I claim and desire to secure by Letters Patent is:

1. An article of manufacture consisting of a core of porous material saturated with 95 a glutinous substance, combined with a cover of porous material and a layer of glutinous substance interposed between said core and its cover.

2. In a non-metallic flexible conduit a 100 helical member composed of a core of porous material saturated with a glutinous sub-

stance, having a cover of porous material and a layer of glutinous substance interposed between said core and its cover, combined with longitudinal threads interwoven with the helical member.

3. The process of manufacturing cord which consists first of subjecting a porous core to a bath of glutinous substance, then

wrapping around said core when the glutinous substance thereon is in a fresh condition 10 a porous covering, and then twisting the said core and its cover tightly together.

In testimony whereof I have hereunto set my hand this eighth day of February, 1923.

FRANK D. SAYLOR.
